BRUSHLESS SHAVING PREPARATION

Richard Thomas, Bromborough, England, and Harry Whitham, deceased, late of Upton, Wirral, England, by May Whitham, executrix, Upton, Wirral, England, assignor to Lever Brothers Company, Cambridge, Mass., a corporation of Maine

No Drawing. Application October 24, 1940, Serial No. 362,606. In Great Britain November 18, 1939

4 Claims. (Cl. 167—85)

The present invention relates to shaving preparations and more particularly to shaving compositions of the so-called brushless type. Unlike brushless shaving creams of the prior art, however, the present shaving preparations may be prepared without a substantial moisture content, and may even be in a substantially anhydrous condition. In addition, the preparations may be produced in stick-like form whereby the compositions may be applied directly to the face without the use of any applicator other than the stick itself.

The brushless shaving creams of the prior art generally comprise a water and oil emulsion prepared by emulsifying, or beating to a cream-like consistency, water and fatty materials with the assistance of emulsifying agents such as soap. A moisture content of the order of at least 50% is conventional. A substantial moisture content has been thought to be essential heretofore to impart to the compositions the lubricating, hair-softening and other properties required for shaving purposes.

The brushless shaving creams of the conventional type being of moist cream-like consistency, generally are inconvenient and, to some, objectionable to use. This is particularly true in the application of the compositions to the face which necessitates the use of applicators, normally the fingers of the user. The prior art compositions generally are packaged in metal tubes which are inconvenient to handle, are generally wasteful, and add to the cost of the final product.

We have discovered that the shaving preparations of our invention, unlike the prior art compositions, may be prepared without any substantial water phase and at the same time may have the lubricating, hair-softening and other properties desired in good grade shaving assistants. Moreover, the consistency of the compositions of our invention may be predetermined to provide a preparation both sufficiently solid to be molded in stick-like form and sufficiently plastic when rubbed on the moistened face of the user to leave a layer, preferably opaque, having the necessary lubricating and other properties for shaving purposes. As a result the compositions when prepared in stick-like form may be applied to the face by direct application, i. e., without the use of any applicators other than the stick itself.

In carrying out our invention, the major proportion of our compositions preferably comprises a mixture of vegetable oil and a waxy ingredient. The particular vegetable oil or waxy ingredient selected is not critical. We prefer, in most cases, to use an oil of the type of sesame, groundnut or olive oil, and the waxes which we prefer to use are the readily available spermaceti or ozokerite. The waxy ingredients, it is well-known, impart non-vanishing characteristics to the com-

position. In some instances, we have found it desirable also to incorporate a small proportion of stearine.

It will be apparent that compositions composed of the above ingredients will be substantially insoluble in water and for desirable shaving characteristics, we have found it is desirable to impart hydrophilic properties to the mixture. Any conventional emulsifying agents may be utilised in sufficient amount to accomplish this result whereby a thin continuous layer or smear of the wax and oil composition is readily left on the wetted skin when the stick is gently rubbed thereon. Among the emulsifying agents which may be utilised for desirable results are soap, monoglycerides, and the fatty acid esters of polyglycerol, particularly the partial esters which contain unesterified hydroxyl groups. These latter compounds may be prepared, for example, by partially esterifying tri-tetra glycerol with the fatty acids derived from vegetable oils.

The use of a mixture of fatty acid esters of polyglycerol of the type described above also is preferred for its action in improving the rinsing properties of the preparation whereby the composition readily may be removed from the face and razor. In general, an amount of from 2-4% of the fatty acid esters of polyglycerol has been found to be desirable.

If desired, the compositions of our invention may have incorporated therewith an indicator such as a pigment, dyestuff or opacifier, whereby the application of the composition to all parts of the surface to be shaved is readily indicated. It is generally preferred to utilise a harmless metal oxide such as titanium oxide, although other such ingredients capable of indicating the presence of the compositions on the face may be used.

The use of perfumes and other desirable ingredients known to the prior art is included within the scope of our invention. It will be apparent to one skilled in the art that the incorporation of such ingredients may be varied over a wide range provided the desired properties of the composition are not adversely affected.

The ingredients preferably are selected, as described above, to form a shaving preparation which is practically insoluble in water, but possesses the hydrophilic, lubricating and other properties required for shaving purposes. The proportions of the ingredients may be varied over a wide range provided the composition possesses the necessary consistency to be molded into stick form. In general, the consistency should be similar to that of an ordinary stick of shaving soap.

A shaving preparation in accordance with the preferred form of our invention, for example, may consist of a blend of sesame, groundnut, cottonseed or olive oil with spermaceti or ozokerite, and a small proportion of stearine, to-

gether with minor proportions of emulsifying substances such as soap, monoglycerides, and fatty acid esters of polyglycerol, and an indicator. The ingredients preferably are heated to a temperature at which they are sufficiently plastic to be readily worked, whereupon they may be agitated to produce a homogeneous composition. After mixing is completed, the composition may be placed into form-imparting means and permitted to cool.

The following is a specific example of the composition of a brushless shaving stick in accordance with the present invention:

	Parts
Sesame oil	38.75
Spermaceti	45.00
Stearine	7.50
Tallow soap	1.50
Partial polyglycerol fatty acid esters	4.00
Titanium oxide	2.00
Perfume	1.25

In preparing a brushless shaving stick of this composition, the soap is added to the oil and the temperature raised to 180 to 190° C. and maintained at that point until the soap has completely dissolved. The solution is then allowed to cool to 80° C. The polyglycerol fatty acid esters and the titanium oxide are rubbed together, the stearine is added thereto and the mixture, heated to 80° C. poured into the solution of soap in oil and gently stirred. The spermaceti, melted and brought to a temperature of 80° C., is added and the whole mixture gently stirred until the temperature has fallen to 50° C. when the perfume is added. Stirring is continued until the temperature has fallen to about 45° C., the mixture is then poured into molds and allowed to cool to room temperature. The solidified mass is removed from the molds and cut and trimmed to the desired size.

As described above, it is preferred to utilize the ingredients of our improved shaving preparations in such proportion that there is formed a mixture possessing the desired lubricating, hair-softening and other properties desired for shaving purposes which may be molded into stick form and may be applied as a thin layer on the face of the user without the use of any applicator other than the stick itself. To indicate more specifically, the variations in proportions of ingredients to which our invention is susceptible, the following ranges of ingredients, if used, are preferred:

	Parts
Vegetable oil	30 to 60
Waxy substance	30 to 50
Stearine	5 to 10
Soap	1.5 to 5
Polyglycerol fatty acid esters	2.0 to 4.0
Indicator	0.5 to 4.0
Perfume	0.5 to 1.5

In general, satisfactory results are obtained when the preparations contain substantially not less than 30% and preferably 33 to 40% vegetable oil, not less than 30% and preferably 40 to 45% waxy ingredient, not more than 10% and preferably 5 to 9% emulsifiers, and not more than 15% or preferably 6 to 11% other ingredients.

It will be apparent that our invention is susceptible to many variations and all such variations are intended to be included within the scope of the following claims.

We claim:

1. A brushless shaving preparation comprising a stick of a substantially solid mixture of 38.75 parts sesame oil, 45 parts spermaceti, 7.5 parts stearine, 1.5 parts tallow soap, 4 parts partial polyglycerol fatty acid esters, 2 parts titanium oxide, and 1.25 parts perfume, whereby said preparation may be applied directly to the face without the use of an applicator other than the stick itself.

2. A substantially non-aqueous brushless shaving preparation in stick-like form and adapted to be applied directly to the face without the use of an applicator other than the stick itself, said preparation comprising substantially 33 to 40 parts vegetable oil, 40 to 45 parts wax, and 5 to 9 parts of a glycerol ester type emulsifying agent for imparting hydrophilic properties to said preparation.

3. A substantially non-aqueous brushless shaving preparation in stick-like form and adapted to be applied directly to the face without the use of an applicator other than the stick itself, said preparation comprising substantially 33 to 40 parts vegetable oil, 40 to 45 parts wax, 5 to 10 parts stearine, 1.5 to 5.0 parts soap, 2.0 to 4.0 parts polyglycerol fatty acid esters, 0.5 to 4.0 parts indicator for rendering the preparation visible when applied to the skin, and 0.5 to 1.5 parts perfume.

4. A substantially non-aqueous brushless shaving preparation in stick-like form and adapted to be applied directly to the face, formed of a mixture comprising approximately 30% to 60% of a vegetable oil and approximately 30% to 50% of a waxy substance so that the mixture is sufficiently solid to be self-supporting when applied to the face without the use of an applicator other than the stick itself and sufficiently plastic when rubbed on the face to leave a layer of the mixture, and an emulsifying agent of the glycerol ester type in an amount of not more than 10% for imparting hydrophilic properties to said preparation.

RICHARD THOMAS.

MAY WHITHAM,

*Executrix of the Estate of Harry Whitham,
Deceased.*
